MACHINE FOR SHAPING SHOE UPPERS
OVER LASTSCorwin W. Baker, Stoneham, Mass., assignor to
United Shoe Machinery Corporation, Flemington, N. J., a corporation of New Jersey

Application July 23, 1941, Serial No. 403,737

21 Claims. (Cl. 12—7)

This invention relates to machines for shaping shoe uppers over lasts, and is herein illustrated as embodied in a lasting machine in the use of which successive portions of an upper are progressively tensioned and worked into lasted position on the insole of the shoe.

The object of the invention is to provide an improved machine, simple in construction and operation, for lasting in a quick and effective manner shoes in which cement is used to secure the overlasted margin of the upper to the insole.

With this object in view, a feature of the invention resides in the combination with upper gripping means which both feeds the work and tensions the upper over the last, of means adjacent to said gripping means for progressively and substantially continuously laying the margin of successive portions of the tensioned upper over an insole on the last and subjecting the overlaid margin to a rapid series of pressure impulses, whereby the upper is forced into permanent adherence to the insole and the tensioning of succeeding portions of the upper by the gripping means is aided.

In the illustrated machine the margin laying means consists of a continuously driven rotary wiper the axis of rotation of which is preferably substantially parallel to the bottom of the last and the direction of movement of the operative portion of which is inward across the margin of the insole. As shown, the wiper comprises a disk which is disposed in a plane substantially perpendicular to the bottom of the last and has spaced projections upon its periphery so that it not only wipes the margin of the upper over the insole but also continually pounds or subjects the said margin to a rapid series of pressure impulses.

Invention is also to be recognized in a mounting for such a wiper constructed and arranged to permit angular change in the path of movement of the wiper with respect to the edge of the insole in order to provide a greater or less component of wiping force longitudinally of the edge of the margin of the upper, for the purpose of distributing the upper material most advantageously to produce a smooth shoe bottom.

A further feature of the invention resides in a pair of obliquely positioned power driven feed rolls arranged to grip the margin of an upper on a last and tension the upper over the last and to feed the last and shoe progressively, in combination with means for moving the axes of the feed rolls angularly with respect to the bottom of the last to vary the tensioning effect

of the rolls upon the upper. In the embodiment of the invention shown herein the axes of the feed rolls are normally maintained at a predetermined angle to the bottom of the last suitable to produce the minimum tension desired in the shoe being lasted, and means is provided whereby the operator may shift the axes of the rolls at will, to increase the tension at those portions of the shoe where a stronger pull is required.

The above and other features of the invention, including various novel details of construction and combinations of parts, will now be described in detail in connection with the accompanying drawings, in which

Fig. 1 is a view of the machine in front elevation;

Fig. 2 is a plan view of the operating instrumentalities of the machine;

Fig. 3 is a fragmentary detail view of a portion of the driving mechanism for the gripper rolls as seen from the rear of the machine, the view being partly in section upon the line III—III in Fig. 2;

Fig. 4 is a view in side elevation showing the relation of the work to the gripper rolls;

Fig. 5 is a fragmentary view illustrating the action of the rotary wiper upon the work;

Fig. 6 is a plan view of the toe portion of a shoe bottom which has been operated upon; and

Fig. 7 shows a modified construction in which one of the gripper rolls has associated with it means for imparting pressure impulses to an insole upon a last bottom.

Referring now to the drawings, 10 indicates a base upon which is supported a table 12. Upon this table is a gripper support comprising a base 14 and an upright 16. The base 14 is slidable upon the table and is constrained to move in a circular path by an arcuate guide member 18, which is secured to the table top. Bolts 20, 22, which pass through arcuate slots 24, 26, in the base 14, are threaded into the table 12 and prevent the base 14 from rising therefrom.

A pull spring 28, anchored at one end to an eye bolt 30 mounted in a stationary bracket 32, is attached to a hook 34 which projects laterally from the upright 16, as shown in Fig. 2. The spring 28 is always in a state of tension and tends to draw the carrier 14, 16, toward the left as viewed in Fig. 2 and to hold it against an adjustable stop screw 36 carried by a stationary bracket 38.

In order to swing the carrier toward the right against the tension of the spring 28 there is pro-

vided a chain 40 which is connected to the carrier by means of a hook 42 (Figs. 1 and 3) and passes around pulleys 44, 46 to a treadle 48 mounted in the base of the machine. Depression of this treadle will cause the carrier to be swung angularly toward the right until its movement is stopped by an adjustable stop screw 50 carried by a stationary bracket 52 which is bolted to the table 12.

The upright 16 has two rearwardly projecting ears 54, 56 through which are threaded screws 58, 60 having conical points which constitute pivots for an elongated lower gripper roll shaft bearing member 62 (Fig. 3). The member 62 extends forward through an opening 64 in the upright 16 and in it is journaled a shaft 66 upon the forward end of which is affixed a knurled gripper roll 68. A gear 70 secured on the rear end of the shaft 66 meshes with a similar gear 72 secured on the rear end of a shaft 74 which is journaled in a stationary upper bearing member 76 projecting forward from the upright 16. Secured on the forward end of the shaft 74 is an upper knurled gripper roll 78 and affixed to its rear end is a pulley 80 which is continuously rotated by a belt 82 driven by a pulley 84 comprising part of a conventional speed reducing mechanism 86 driven by a shaft 88 from a motor 90.

The gears 70, 72 mesh loosely, as shown in Fig. 3, approximately in the axis of the pivot screws 58, 60, permitting the bearing member 62 and the lower gripper roll 68 to swing up or down about the pivotal axis without disengaging the gears from each other. The lower pivoted bearing member 62 is supported and pressed upward by a rather stiff compression spring 92, the tension of which may be adjusted by manipulating a screw 94 threaded into the base member 14. A stop screw 96 in a stationary bracket 98 serves to determine adjustably the upper limit to which the member 62 can be raised by the spring 92 and, consequently, the nearness of approach of the lower gripper roll 68 to the upper gripper roll 78.

For the purpose of lowering the lower gripper roll to permit the margin of an upper to be inserted between the rolls, there is provided a chain 100 which is connected to a treadle 102 mounted in the base of the machine.

A rotary wiper 104 is provided for laying the margin of the tensioned upper over the bottom of the last and forcing it into smooth contact with the insole thereon. The wiper 104 is rotatably journaled upon a stud 106 which is secured in an angle plate 108 by a set screw 110 as shown in Figs. 1 and 2. The base of the angle plate 108 is mounted upon a stationary bracket 112 which is secured upon the table 12 by bolts 114 and an arcuate guide 116, secured to the upright face of the bracket 112 by screws 118, cooperates with a corresponding arcuate groove in the back of the angle plate 108 to restrict sliding movement of the angle plate upon the bracket to a circular path, the center of curvature of which is approximately at the point where the wiper engages the shoe. Bolts 120, 122, which pass through arcuate slots 124, 126 in the angle plate 108, are threaded into the bracket 112 and serve to secure the angle plate in adjusted position therein. When these bolts are loosened slightly, the angle plate and, consequently, the axis of rotation of the wiper 104 can be adjusted angularly in a vertical plane. Expressed in another way, the plane of the wiper can be adjusted to any desired inclination to the vertical.

The wiper has a series of spaced projections 128 around its periphery. These projections act as pounding elements to impart a rapid series of blows or pressure impulses to the work when the wiper is rotated. Secured to the wiper is a pulley 130 engaged by a belt 132 which passes around idle pulleys 134 and thence around a pulley 136 upon the motor shaft 88, by which the belt is driven to rotate the wiper continuously at a fairly high speed.

Two side gages are provided to aid in positioning the shoe properly in relation to the gripper rolls and the wiper. These gages comprise the rubber faced rolls 138, 140, both of which are freely rotatable. The roll 138 is journaled upon a horizontal stud carried by the lower end of an arm 142 mounted in a block 144 from which extends a threaded stud 146. The stud 146 passes through a bracket 148 which is adjustably secured to the top of the angle plate 108 by bolts 150 passing through slots 152 in the bracket. A nut 154 threaded upon the stud 146 serves, when tightened, to secure the block 144 in any desired position of angular adjustment about the axis of the stud.

The roll 140 is similarly mounted on the top of the stationary bearing member 76 by an arm 156, a block 158, and a bracket 160. The two rolls 138, 140 serve as side gages for aiding the operator in presenting the shoe properly to the gripper rolls 68, 78 and the rotary wiper 104.

In order to provide a bottom rest for the shoe, a guard 162 (see Figs. 1 and 4) is arranged immediately in front of the lower gripper roll 68. This guard is mounted upon a bracket 164 depending from the bearing 62, the guard being secured to the bracket by a screw 166. As shown in Fig. 4, the insole 168 of a shoe 170 assembled upon a last 172 is positioned against the shoe bottom rest 162 with the margin 174 of the shoe upper extending horizontally between the gripper rolls and the side of the shoe against the side gage roll 140.

A modified form of lower gripper roll structure is shown in Fig. 7. In this form, the shaft 66 is hollow and passing through it is a shaft 176 upon the rear end of which is secured a pulley 178 driven by a belt 180 from any convenient source of power. The front end of the shaft 176 carries a rotary cam disk 182, the outer face of which is oblique to the axis of said shaft, with the result that it acts continually to impart a rapid series of blows or pressure impulses to the insole 168 and the last 172. This is advantageous in that it insures that the marginal portion of the insole will lie flat and smooth against the last bottom at the place where the lasting operation is being performed, which is particularly important when flimsy insoles are being used since such insoles have some tendency to crumple. The rapidly repeated impulses on the last also have a tendency to aid in tensioning the upper of the shoe, which is held firmly between the gripper rolls. When the cam disk 182 is used, the guard 162 is, of course, removed.

In the operation of the machine the stop screw 36 is adjusted to produce such a degree of obliquity of the shaft 74 to the direction of feed of the work that the rolls 68, 78 will exert the desired minimum amount of tension upon the upper of the shoe. The treadle 102 is depressed to permit the marginal portion 174 of the shoe upper to be inserted between the rolls 68, 78 with the shoe positioned against the side gages 138, 140 and the bottom rest 162 after which the treadle

182 is released, whereupon the rolls 68, 78 seize the margin 174 of the upper and simultaneously feed the shoe in the direction indicated by the arrow on Fig. 2 and tension the upper over the last.

As the margin of the upper leaves the rolls 68, 78 it comes into the path of the rapidly rotating wiper 184 which lays the margin down upon the insole and, by a combined wiping action and a rapid series of pressure impulses, forces the upper into permanent adherence to the insole, both the upper and the insole having been previously coated with cement. As the operation proceeds to a portion of the shoe where a stronger pull upon the upper is needed to tension it properly over the last, the treadle 48 may be depressed, causing the axis of the gripper rolls to be swung in a clockwise direction, as viewed in Fig. 2, until stopped by the stop screw 50. The tensioning effect is thus increased to the desired extent until a portion of the shoe is reached where less tension is required, whereupon the treadle 48 is released, the lasting operation proceeding uninterruptedly, regardless of changes in the tensioning force.

As is apparent from Figs. 1 and 2, the plane of rotation of the disk 184 is so inclined with respect to the edge of the last that the upper margin 174 is wiped both inwardly and longitudinally of the last away from the gripper rolls, in the direction in which the shoe is moving. The large number of pressure and wiping impulses imparted by the projections 128 on the wiper cause the upper material to be distributed evenly substantially continuously, and laid smoothly on the bottom face of the insole and when working around curves, as at the toe of the shoe, to produce a large number of narrow pleats or folds, as shown at 184 in Fig. 6. The continual pounding of the last by the projections 128, acting through the margin of the upper and the insole, also aids in forcing the last tightly into the upper in the region where the latter is held and is being tensioned by the gripper rolls.

Having described the invention, what is claimed as new and desired to be secured by Letters Patent of the United States is:

1. In a machine for shaping uppers over lasts, a pair of power-driven rolls arranged to grip the margin of an upper upon a last and to effect feeding movement thereof, the axes of said rolls being oblique to the last bottom and so disposed with respect to the path of feeding movement as to tension the upper over the last, and means for moving said axes angularly with respect to said path of feeding movement to increase or diminish the tensioning effect upon the upper.

2. In a machine for shaping uppers over lasts, the combination, with means for laying the marginal portion of an upper inwardly over an insole on a last, of a pair of power-driven rolls arranged to grip the margin of the upper and to effect feeding movement thereof, the axes of said rolls being oblique to the last bottom and so disposed with respect to the path of feeding movement as to tension the upper over the last, and means for moving said axes angularly with respect to said path of feeding movement to increase or diminish the tensioning effect upon the upper.

3. In a machine for shaping uppers over lasts, the combination of a pair of power-driven rolls arranged to grip between them the marginal portion of an upper and effect feeding movement thereof, means for determining a position of the shoe in which the last bottom is oblique to the

axes of said rolls, whereby the rolls tension the upper heightwise of the last during the feeding movement, said means including a wiper for laying the marginal portion of the upper inwardly over an insole on the last, and means for moving said axes angularly with respect to the shoe-positioning means, to increase or diminish the tensioning effect upon the upper.

4. In a machine for shaping uppers over lasts, a pair of power driven rolls arranged to grip the margin of an upper upon a last and to effect feeding movement thereof, the axes of said rolls being oblique to the last bottom and so disposed with respect to the path of feeding movement as to tension the upper over the last, and means for varying the obliquity of said axes to increase or diminish the tensioning effect upon the upper as the operation proceeds around the last.

5. In a machine for shaping uppers over lasts, a shoe bottom rest, a pair of power driven feed rolls arranged by engagement with the marginal portion of an upper mounted on a last to feed the last and shoe past said bottom rest and to tension the upper over the last, and means operable during the feeding operation for moving the axes of said feed rolls angularly with respect to the bottom face of a sole on the last to vary the tensioning effect of the feed rolls upon the upper.

6. In a machine for shaping uppers over lasts, a shoe bottom rest, a pair of power driven feed rolls arranged to grip the marginal portion of an upper mounted on a last and to feed the last and shoe past said shoe bottom rest, adjustable means for normally maintaining the axes of the feed rolls at a predetermined angle to the face of a sole held against said rest, and operator controlled means operable during the feeding operation for moving said axes to a different angle with respect to the face of the sole.

7. In a machine for shaping uppers over lasts, a shoe bottom rest, a pair of power driven feed rolls arranged to grip the marginal portion of an upper mounted on a last and to feed the last and shoe progressively past said shoe bottom rest, said rolls being rotatable about axes inclined relatively to the bottom face of an insole on the last to cause the upper to be tensioned heightwise of the last during the feeding operation, a movable support for said feed rolls, means for predetermined different adjusted positions of said support, and means enabling the operator at will quickly to shift said support to one or the other of said predetermined positions in operating upon different portions of the shoe bottom.

8. In a machine for shaping uppers over lasts, a shoe bottom rest, a pair of power driven feed rolls arranged to grip the marginal portion of an upper mounted on a last and to feed the last and shoe progressively past said shoe bottom rest, said rolls being rotatable about axes inclined relatively to the bottom face of an insole on the last to cause the upper to be tensioned heightwise of the last during the feeding operation, a support for said feed rolls movable to vary the inclination of the feed rolls relatively to the bottom face of the insole and thus to vary the tensioning effect of the rolls on the upper, and means enabling the operator at will to effect a quick adjustment of said support in operating along different portions of the shoe bottom.

9. In a machine for shaping uppers over lasts, the combination of means for gripping and pulling successive portions of an upper over a last, and means adjacent to the first-named means for progressively and substantially continuously lay-

ing the margin of said successive portions of the upper over an insole on the last and subjecting the overlaid margin to a rapid series of pressure impulses.

10. In a machine for shaping uppers over lasts, the combination of continuously operating means for gripping and pulling successive portions of an upper over a last, and means arranged to act substantially continuously on the margin of the upper in a location adjacent to said first-named means to wipe the margin inward over an insole on the last while imparting to it a plurality of pressure impulses heightwise of the last.

11. In a machine for shaping uppers over lasts, the combination of means for gripping and pulling successive portions of an upper over a last, and means adjacent to the first-named means for laying one section of the margin of said successive portions of the upper over an insole on the last and subjecting it to a rapid series of pressure impulses while another section of said margin is in the grip of said first-named means.

12. In a machine for shaping uppers over lasts, the combination of gripping means for tensioning successive portions of an upper over a last, and means for applying pressure impulses to the margin of one portion of the upper to force it into permanent adherence to an insole on the last while another portion of the upper is being tensioned by said gripping means.

13. In a machine for shaping uppers over lasts, the combination of means for gripping and pulling successive portions of an upper over a last, and a combined rotary wiping and pounding tool arranged beside said means in a position to wipe the margin of the tensioned upper over an insole on the last and to pound it down upon said insole.

14. In a machine for shaping uppers over lasts, a combination upper tensioning and feeding device, and a combined wiping and pounding tool cooperatively related thereto to wipe the margin of the tensioned upper over an insole on the last and to pound it down upon said insole.

15. In a machine for shaping uppers over lasts, the combination of gripping means for seizing an upper between cooperating elements and tensioning it over a last, a rotary wiper, and means for effecting continuous rotation of said wiper about an axis substantially parallel to the last bottom and oblique to the edge thereof at the point being operated upon.

16. In a machine for shaping uppers over lasts, upper tensioning devices, and a rotary wiper consisting of a disk disposed in a plane substantially perpendicular to the bottom of the last and having spaced projections upon its periphery, the axis of rotation of the disk being so located that said projections engage and wipe the margin of the tensioned upper both inwardly of the last and longitudinally thereof away from the tensioning devices.

17. In a machine for shaping uppers over lasts, means for tensioning an upper over a last in different locations along the edge of the last bottom, and means acting on the marginal portion of an insole on the last in each location where the upper is thus tensioned to impart to the last and shoe a plurality of pressure impulses heightwise of the shoe to assist in increasing the tensioning effect of said first-named means on the upper.

18. In a machine for shaping uppers over lasts, a pair of power-driven feed rolls arranged by engagement with the marginal portion of an upper mounted on a last to feed the last and shoe and to tension the upper over the last, and means acting simultaneously on the margin of the insole to impart to it a rapid series of pressure impulses heightwise of the last.

19. In a machine for shaping uppers over lasts, a side gage arranged to engage the side of a shoe upon a last near the edge of the insole, a rotary wiper arranged to lay the margin of the shoe upper inward over the insole, and a mounting for said wiper constructed and arranged to permit angular change of the path of movement of the wiper with respect to the edge of the insole.

20. In a machine for shaping uppers over lasts, a pair of power driven feed rolls arranged to feed the margin of an upper and to tension the upper over a last, and means for imparting a rapid series of pressure impulses to the margin of an insole upon the last at the location where the upper is tensioned.

21. In a machine for shaping uppers over lasts, a rotary hollow shaft, a feed roll upon said shaft arranged to engage the inner face of the margin of an upper being tensioned over a last, a second rotary shaft, inside said hollow shaft, and a rotary pressure impulse tool carried by said second shaft in position to operate upon an insole upon the last.

CORWIN W. BAKER.
